POWER-DRIVEN SURF BOAT

Arthur R. Swenson, 6051 Glen Arms Drive,
Oakland, Calif.

Filed July 24, 1959, Ser. No. 56,935

Term of patent 14 years

(Cl. D71—1)

FIG. 1

FIG. 2

FIG. 3

FIG. 4

FIG. 5

FIG. 6

FIGURE 1 is a top plan view of a power-driven surf boat;

FIGURE 2 is a side elevational view thereof;

FIGURE 3 is a rear elevation of the power-driven surf boat;

FIGURE 4 is a top perspective view thereof; and

FIGURES 5 and 6 are bottom plan and front elevational views, respectively, thereof.

The outboard motor shown in broken lines in FIGURES 1 and 2 is included for illustrative purposes only.

I claim:

The ornamental design for power-driven surf boat, as shown and described.
